UNITED STATES PATENT OFFICE.

LUELLA STILWELL KINNARD, OF CHICAGO, ILLINOIS.

TOILET-BOX.

1,224,552.

Specification of Letters Patent.

Patented May 1, 1917.

Application filed December 16, 1915. Serial No. 67,296.

To all whom it may concern:

Be it known that I, LUELLA STILWELL KINNARD, a citizen of the United States, and resident of Chicago, in the county of 5 Cook and State of Illinois, have invented certain new and useful Improvements in Toilet-Boxes, of which the following is a specification.

The object of this invention is to provide 10 a toilet box adapted particularly for holding face powder or rouge, and capable of being secured to the dress or clothing of the user where it will form an article of adornment with the box itself in convenient position for use, but so covered and concealed 15 as not to lessen the ornamental appearance of the article.

The invention consists generally in the 20 constructions and combinations hereinafter described, and particularly pointed out in the claims.

In the drawings Figure 1 is a perspective view of a toilet box embodying my invention,

25 Fig. 2 is a view illustrating the manner of wearing the box secured to the clothing of the wearer.

Fig. 3 is a perspective view partly broken away to show the interior construction.

30 In all of the drawings 2 represents the box or receptacle proper, which is preferably of cylindrical form having an open top and of suitable size to be worn upon the person when supported and arranged in the 35 manner herein described.

The outer wall of the box is preferably surrounded by a covering 3 of suitable fabric, which may be drawn inward at the bottom and connected to or made integral with 40 a downwardly extending flexible stem 7. The box is also provided with a cover 4 preferably telescoping within the wall of the box. The cover is preferably provided with a small loop or handle 10, which may be 45 grasped when the cover is to be removed or inserted. The edge of the cover is preferably of flexible material adapted to form sufficient frictional contact with the wall of the box to cause the cover to be retained in position. 50 The under side 11 of the cover 4 is preferably provided with a soft, woolly or fuzzy surface to which the face powder, rouge, or similar material, will adhere and which forms a convenient means of applying the 55 powder or rouge to the face or other part of the flesh of the user.

Secured to the outer surface of the box are a series of flexible and preferably overlapping projections 5. These may be formed of ribbon or other suitable fabric or material and they are preferably grouped around the outer surface of the box substantially as shown in Fig. 1, and are preferably shaped so as to imitate the petals of a flower. They form a large flexible base for 60 the box, which, when the box is to be worn by the user, comes against the clothing, and bearing against the person keeps the box in the desired position. Some of the flexible projections 6 may be shaped to imitate 65 the leaves of a plant, as indicated in Figs. 1 and 2. The projections 6 increase the size and add to the firmness and stability of the base formed by the projections 5.

In the form shown in the drawings the 70 box and the surrounding projections 5 are arranged and colored to imitate a rose and the top of the cover is preferably formed and colored to imitate the center of such flower. The projections 5 imitate the rose 75 petals in form and color and the projections 6 are preferably colored and shaped to imitate the leaves of the rose plant.

I may also further add to the ornamental effect of the toilet box by tying a knot of 80 ribbon 8 on the stem 7 and the depending parts 9 thereof may be made into pockets to contain a small mirror or other desired toilet article.

It will be understood that the form of the 85 projections 5 and 6 may be changed and these parts may be made of any desired color or colors, so that the completed article may be made to resemble any desired flower, instead of a rose, such as a lily, a chrysanthemum, an orchid, a dahlia, a spray of clematis, or a bunch of any of these or other flowers.

If preferred the stem 7 may be omitted 100 and in this instance the box with its surrounding projections forming the flexible base will serve as a toilet box to be supported upon a table or other article of furniture. In this instance, however, the cover of the box will imitate the center of a flower and the surrounding flexible projections constituting the base will be made to imitate the 105 form and color of any desired flower or spray or bunch thereof, in the manner already described.

I may also make the box and its surrounding base of suitable size to be secured upon a 110

slipper, preferably upon the instep portion thereof. Where the wearer has a box of this kind secured upon each slipper one may be used for face powder and the other for rouge. Other locations for the device will suggest themselves to the user.

I do not limit myself to the details of construction as the same may be varied in many particulars without departing from my invention.

I claim as my invention:

1. A toilet article comprising, in combination, a box having an open top, a fabric covering the sides of the box and drawn inward at the bottom and having the box attached thereto, a cover for the box, and a series of flexible projections extending outwardly from the walls of the box and shaped and colored to imitate the petals of a flower.
2. A toilet article comprising, in combination, a box having an open top, a cover for the box formed to fit within the box and hav-

ing a flexible edge to frictionally engage the inside of the wall of the box, and a series of flexible projections extending outwardly from the walls of the box and shaped and colored to imitate the petals of a flower.

3. A toilet article comprising, in combination, a box having an open top, a series of flexible projections extending outwardly from the walls of the box and shaped and colored to imitate the petals of a flower, and a cover for the box formed to fit within the box and frictionally engage the inner surface of the wall, the under face of the cover being provided with a soft surface and the outer face made to imitate the center of the flower represented by the colored petals.

In witness whereof, I have hereunto set my hand this 13 day of December 1915.

LUELLA STILWELL KINNARD.
